UNITED STATES PATENT OFFICE.

LÉON DION, OF BOSTON, MASSACHUSETTS, ASSIGNOR TO AMERICA MARINE COMPANY, OF NEW YORK, N. Y., A CORPORATION OF SOUTH DAKOTA.

PROPELLING APPARATUS FOR VESSELS.

SPECIFICATION forming part of Letters Patent No. 737,213, dated August 25, 1903.

Application filed September 6, 1902. Serial No. 122,385. (No model.)

To all whom it may concern:

Be it known that I, LÉON DION, of Boston, in the county of Suffolk and State of Massachusetts, have invented certain new and useful Improvements in Propelling Apparatus for Vessels, of which the following is a specification.

This invention relates to means for impelling navigable vessels, and embodying downwardly-opening longitudinal channels formed in the bottom of the hull, and chains or paddles supported by drive-wheels in said channels and moved longitudinally therein to exert pressure upon the water in the lower portions of said channels. In another application for Letters Patent of the United States filed by me concurrently herewith I have shown one embodiment of said invention.

The present invention consists in certain improvements in the construction of the chains or paddles, in the drive-wheels which support and impel the same, and in other portions of the apparatus, all of which I will now proceed to describe and claim.

In the accompanying drawings, forming a part of this specification, Figure 1 represents a longitudinal section of a portion of one of the channels in the hull of a navigable vessel and a side elevation of one of the drive-wheels and a portion of the chain of paddles located in said channels, the plane of the section on which Fig. 1 is taken being indicated by the line 1 1 in Fig. 2. Fig. 2 represents a section on line 2 2 of Fig. 1. Figs. 3 and 4 represent perspective views of a unit of the chain.

The same reference characters indicate the same parts in all the figures.

In the drawings, *a a* represent the sides or walls of a channel *a'*, which extends longitudinally in the bottom portion of the hull of the navigable vessel and opens downwardly. In practice there will be a plurality of these channels, one or more located at one side of the longitudinal median line of the bottom of the hull and one or more at the opposite side of said line, as shown in the above-mentioned application. In the drawings of this application I have considered it necessary to show only portions of one of the said chan-

nels and one of the drive-wheels located therein. It will be understood, however, that each channel has two of said drive-wheels, one located at one end portion and the other at or near the opposite end portion, so that 55 the stretches of the chain of paddles supported by said drive-wheels extend lengthwise of the channels and of the hull of the vessel, the lower stretch of paddles being near the open mouth or bottom portion of the 60 channel.

b represents a shaft, which is preferably tubular and is journaled in bearings formed in the walls *a a*. The end portions of the shaft project outside of the channel and are 65 or may be provided with means, such as sprocket-wheels *c*, to engage drive-chains, which communicate motion from a suitable source of power, such as an electric or other motor, to the shaft.

b' represents a hub or web formed on or rigidly affixed to the central portion of the shaft *b*.

b² *b³* represent side plates rigidly affixed to the web *b'*, said plates being of circular form, 75 so that their outer margins constitute two perimeters of a drive-wheel, said margins being bent outwardly at *b³* *b³* and separated by an intermediate peripheral space *b⁴*. The perimeters of the side plates *b²* *b²* are provided with slots or recesses *b⁵*, formed to receive the end portions of the paddles *c*, hereinafter referred to.

The chain of paddles is preferably composed of a series of units, each constructed as shown in Fig. 3. Each paddle *c* has a substantially flat front face extending crosswise of the chain and two coupling members *c'* *c²*, one projecting from the front and the other from the back side of the paddle. The member *c'* is provided with a hook *c⁴*, while the member *c²* is provided with a slot *c⁵*, formed to receive the hook of another chain unit, the several units being coupled together, as clearly shown in Fig. 1. The paddle *c* is made 95 longer than the coupling members *c'* and *c²*, so that its ends project outside of the ends of the coupling members, the ends of the paddles being thus adapted to enter and engage the slots *b⁵* in the drive-wheel, while the coup- 100

ling members are adapted to enter the space b^4 between the two perimeters of the drive-wheel.

c^6 c^6 represent studs projecting outwardly 5 from the ends of the paddles c , said studs entering guide-grooves g , formed in the walls of the passage a' . The engagement of the studs with the guide-grooves prevents the sagging of the stretches of the chain between 10 the drive-wheels, as will be readily seen. The acting faces of the paddles are securely held substantially at right angles with the stretches of the chain, so that when the chain is impelled by the rotation of the drive-wheels 15 the paddles exert pressure upon the water in the lower portion of the channel a' , and thus impel the vessel.

The hub or web b' is preferably provided with concentric annular ribs b^5 , which fit into 20 corresponding annular grooves formed in the inner sides of the side plates b^2 , as shown in Fig. 2. The hub or web b' and the side plates b^2 are securely connected by transverse bolts b^6 , these bolts and the above-mentioned ribs 25 and grooves contributing to form an extremely solid and durable construction. The bearings for the shaft b' are preferably provided with antifriction-rollers i , held in place by suitable holding means, as shown in Fig. 2.

30 In Fig. 4 I show a paddle with a rounded back, while in Fig. 3 the paddle shown is flat at its central portion and rounded at its ends.

I do not limit myself to the details of construction here shown, and may variously 35 modify the same without departing from the spirit of the invention.

It is obvious that each chain of paddles may be driven by but one drive-wheel, which may be located at any desired part of the 40 channel, suitable idle rolls or pulleys being employed to coöperate with the drive-wheel in supporting the chain.

I believe myself to be the first to provide a paddle formed as a chain unit and provided 45 not only with coupling members for engagement with other units, but also with supporting means, such as the studs c^6 , for engaging complementary means, such as the guide-grooves g , to prevent sagging of the chain.

50 I claim—

1. A vessel having a longitudinal channel in its hull, a drive-wheel located in the said channel, having two slotted perimeters separated by an intermediate peripheral space,

and a chain composed of a series of units, 55 each including a paddle, and coupling members rigidly affixed thereto, the paddle being formed to engage the slots in the perimeters of the wheel, while the coupling members are formed to enter the spaces between the said 60 perimeters.

2. A vessel having a longitudinal channel in its hull, a drive-wheel located in said channel, comprising a shaft journaled in bearings in the sides of the channel, a hub or web 65 rigidly affixed to the shaft, and side plates affixed to said web, their perimeters being slotted and separated by an intermediate peripheral space, and a chain composed of a series of paddles formed to engage the slotted 70 perimeters of the side plates, and coupling members connecting said paddles and formed to enter the said intermediate space.

3. A vessel having a longitudinal channel in its hull, antifriction-bearings in the sides 75 of said channel, a shaft journaled in said bearings and extending across the channel, a chain-engaging wheel affixed to said shaft within the channel, a chain engaged with said wheel within the channel and composed 80 of a series of paddles formed to engage the wheel, and coupling members between the paddles, and means outside the channel for rotating said shafts and wheel.

4. A chain of paddles composed of a series 85 of integral units each comprising a paddle, coupling members and supporting members, all formed on the paddle and integral therewith.

5. A vessel having a longitudinal channel 90 in its hull, the walls of said channel having guide-grooves, a drive-wheel mounted on a shaft journaled in said walls, said wheel having two slotted perimeters separated by an intermediate peripheral space, and a chain 95 composed of a series of paddles formed to engage said slotted peripheries and having studs at their ends projecting into said guide-grooves, and coupling members formed on said paddles and shorter than the latter, said 100 coupling members being formed to enter the peripheral space of the wheel.

In testimony whereof I have affixed my signature in presence of two witnesses.

LÉON DION.
